UNITED STATES PATENT OFFICE.

LEON BOCK, OF NEW YORK, N. Y., ASSIGNOR TO SELIKOFF AND SCHAPIRO, INC., OF NEW YORK, N. Y., A CORPORATION OF NEW YORK.

DESIGN FOR A RING SETTING.

Application filed October 11, 1927. Serial No. 23,711. Term of patent 7 years.

To all whom it may concern:

Be it known that I, LEON BOCK, a citizen of the United States, residing in New York, in the county of New York and State of New York, have invented a new, original, and ornamental Design for a Ring Setting, of which the following is a specification, references being had to the accompanying drawing, forming a part thereof.

I claim:

The ornamental design for a ring setting as shown.

LEON BOCK.
